US0D1076910S

(12) **United States Design Patent** (10) **Patent No.:** **US D1,076,910 S**
(45) **Date of Patent:** **** May 27, 2025**

(54) **CALENDAR DEVICE**

(71) Applicant: **SHENZHEN ELECTRON TECHNOLOGY CO., LTD.**, Shenzhen (CN)

(72) Inventors: **Cheng Zhuang**, Shenzhen (CN); **Yonghong Li**, Shenzhen (CN)

(73) Assignee: **SHENZHEN ELECTRON TECHNOLOGY CO., LTD.**, Shenzhen (CN)

(**) Term: **15 Years**

(21) Appl. No.: **29/991,935**

(22) Filed: **Mar. 5, 2025**

(51) LOC (15) Cl. **14-02**

(52) U.S. Cl.

USPC **D14/341**

(58) **Field of Classification Search**

USPC D14/225, 229, 341, 342, 343, 125, 371; D19/20, 60, 21, 24, 25

(57) **CLAIM**

The ornamental design for a calendar device as shown and described.

DESCRIPTION

FIG. 1 is a perspective view of a calendar device showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged view of portion 9 identified in FIG. 1;

FIG. 10 is an enlarged view of portion 10 identified in FIG. 5; and,

FIG. 11 is an enlarged view of portion 11 identified in FIG. 7.

The broken lines in the drawings depict portions of the calendar device that forms no part of the claimed design.

1 Claim, 11 Drawing Sheets
